UNITED STATES PATENT OFFICE.

WALTER ERNEST COLWELL, OF OAKVILLE, ONTARIO, CANADA.

DESIGN FOR A CABINET FOR SOUND-REPRODUCING APPARATUS.

51,716.

Specification for Design.

Patented Feb. 5, 1918.

Application filed October 12, 1917. Serial No. 196,332. Term of patent 14 years.

To all whom it may concern:

Be it known that I, WALTER ERNEST COLWELL, of the town of Oakville, county of Halton, Province of Ontario, Dominion of Canada, a subject of the King of Great Britain, have invented a new, original, and ornamental Design for Cabinets for Sound-Reproducing Apparatus, of which the following is a specification, reference being had

to the accompanying drawings, forming part thereof.

Figures 1 and 2 are respectively elevations of the rear and front sides of the cabinet, illustrating my new design.

I claim:

The ornamental design for a cabinet for sound reproducing apparatus as shown.

WALTER ERNEST COLWELL.
